(57) **CLAIM**

The ornamental design for a light stand, as shown and described.

DESCRIPTION

FIG. 1 is a front, top, and right side isometric view of an ornamental design for a light stand;

FIG. 2 is a rear, top, and left side isometric view of the light stand of FIG. 1;

FIG. 3 is a front elevational view of the light stand of FIG. 1;

FIG. 4 is a rear elevational view of the light stand of FIG. 1;

FIG. 5 is a left side elevational view of the light stand of FIG. 1;

FIG. 6 is a right side elevational view of the light stand of FIG. 1;

FIG. 7 is a top plan view of the light stand of FIG. 1;

FIG. 8 is a bottom plan view of the light stand of FIG. 1; and, FIG. 9 is a front, top, and right side isometric view of the light stand of FIG. 1 including a connection interface shown in dashed lines.

The dash-dash-dash broken lines are included for the purpose of illustrating portions that form no part of the claimed design. The dash-dot-dash lines are included for the purpose of illustrating boundary lines and form no part of the claimed design. The break lines are included for the purpose of illustrating unclaimed portions of varying length.

1 Claim, 6 Drawing Sheets
